(57) **CLAIM**

The ornamental design for a bed display, as shown and described.

DESCRIPTION

FIG. 1 is a front, top perspective view of a first embodiment of a bed display showing our new design;

FIG. 2 is a front view thereof;

FIG. 3 is a right, side view thereof;

FIG. 4 is a left, side view thereof;

FIG. 5 is a top view thereof; and,

FIG. 6 is second embodiment of FIG. 1, shown in a front, top perspective view, the only difference being a mattress and corresponding mattress foundation are in dashed lines.

The broken lines are environmental and form no part of the claimed design.

1 Claim, 5 Drawing Sheets

FIG. 2

FIG. 3

FIG. 4

FIG. 5
